UNITED STATES PATENT OFFICE.

ERNEST H. ARNOLD, OF CLEVELAND, OHIO, ASSIGNOR TO HENRY M. STRONG, OF CLEVELAND, OHIO.

AUTOMOBILE FAN.

Application filed October 14, 1921. Serial No. 507,647.

To all whom it may concern:

Be it known that I, ERNEST H. ARNOLD, a subject of the King of England, resident of Cleveland, county of Cuyahoga, and 5 State of Ohio, have invented new and useful Improvements in Automobile Fans, of which the following is a specification, the principle of the invention being herein explained and the best mode in which I have 10 contemplated applying that principle, so as to distinguish it from other inventions.

My invention relates to automobile fans, its object being to produce a fan which will be efficient in the performance of its function, and which may be produced in an 15 economical manner.

The said invention consists of means hereinafter fully described and particularly set forth in the claims. More specifically, my 20 invention consists of a fan which is made of two parts, a blade member and a hub-member, the major portion of the hub-member consisting of an integral structure drawn from a disk of sheet metal, and provided with bushings at its ends, the one end 25 of said hub-member being shaped to form a pulley and the other end being secured to the blade member, all as will hereinafter be more fully described.

30 The annexed drawing and the following description, set forth in detail certain means embodying my invention, the disclosed means, however, constituting but one of the various mechanical forms in which the principle of the invention may be applied.

In said annexed drawing:

Figure 1 represents a front elevation of a fan embodying my invention, and mounted upon a suitable journal rod.

40 Figure 2 represents a section taken upon the plane indicated by line II-II in Figure 1.

Figure 3 represents a top plan of the blade member of the fan.

45 Figure 4 represents a detail end elevation of the end plate forming part of the pulley.

Figure 5 represents a section taken upon the plane indicated by line V-V in Figure 4.

50 Figure 6 represents an axial section of the unitary drawn sheet metal part of the main hub-member and which constitutes the major portion of the latter, illustrating the form of same prior to the securing of

the blade member thereto, and prior to the 55 application of the end plate.

Figure 7 represents a fragmentary axial section of a hub-member, showing a modified construction thereof.

The illustrated embodiment of my invention comprises two major elements, namely the blade member 1, and the hub-member 2. The particular blade member shown includes four blades 3, 3, radiating from a central disk-like portion 4, and formed at 60 its central portion with a circular opening 5. Suitable struck-up ribs 6 are formed to stiffen the blades, as will be readily understood, and the entire structure just described, in this particular instance, is shown 65 to have been struck up from a single sheet of metal so as to form one integral structure.

The hub-member 2 consists of the main hub-portion and the end disk. The main 70 hub member is drawn from a disk of metal by means of suitable dies into the form shown in Figure 6, in which one end forms a pulley portion 7 and the other end a portion 8 of reduced diameter. A fold 8' 75 forms a flange at one end of the pulley portion, and the shoulder 9 is formed at the other end of said pulley portion, from which shoulder projects the cylindrical end portion 11. The extremity of the portion 8 is of further reduced diameter, its outer 80 dimension being substantially equal to the diameter of the opening 5 in the blade member. A struck-up plate 10, Figures 4 and 5, is provided which has an outer diameter 85 equal to the interior diameter of the cylindrical end 11 of the pulley member, so that said plate will fit within the latter, as shown in dotted lines in Figure 6. After this plate has been so inserted in the pulley portion, the end 11 thereof is spun around the periphery of the disk, as shown in Figure 2, whereby such plate is securely fixed and forms the outer end of the pulley. I 90 prefer to provide a peripheral depression 12 100 for the reception of the metal of the portion 11 so that the end face of said pulley may be perfectly flat, as also shown in Figure 2. The central portion of the plate 10 is provided with an opening 13 surrounded by a 105 flange 14.

The reduced extremity of the end of reduced diameter passes through the central

opening 5 in the blade member, and is spun outwardly and around the exterior of the metal of the blade portion which surrounds said central opening, as shown in Figure 2, whereby the blade portion is secured in a fold of the hub-member and securely fixed therein.

The interior diameter of the openings in the two ends of the hub member are made equal to each other and in each of these openings is driven a suitable bushing 14', which provides the bearing for the journal rod 15 upon which the fan is mounted.

The above construction may be slightly modified, as shown in Figure 7, wherein I have shown an end plate 10 which, instead of being enclosed within a fold formed by the extremity of the main hub-portion, itself forms a fold, as shown, and encloses the flange 9 of the pulley, as will be readily understood.

By constructing the main portion of the hub-member as described, and especially by leaving the hub end thereof open and afterward closing it with a separate plate, I am enabled to insert upon the interior of the hub, ball or roller bearings which may at times be desirable substitutes for the bushings 14'.

30 What I claim is:

1. A hub-member for an automobile fan, comprising an integral seamless sheet of metal shaped to form a pulley portion at one end and a portion of different diameter from that of said pulley portion, at the other end; together with a separate end plate secured to said pulley portion.

2. A hub-member for an automobile fan, comprising an integral seamless sheet of metal shaped to form a pulley portion at one end and a portion of different diameter from that of said pulley portion at the other end; together with a separate end plate forming the outer end of the pulley; the outer end of said pulley portion and the said plate being connected by means of a fold formed on the one and closing the peripheral portion of the other.

3. A hub-member for an automobile fan, comprising a main part drawn from an integral sheet of metal to form a pulley portion at one end thereof and a portion of reduced diameter at the other end thereof; said pulley portion being formed at each end thereof with a flange; and a separate

plate forming the outer end of the pulley and having its peripheral portion in engagement with the outer flange of said pulley portion.

4. A hub-member for an automobile fan, 60 comprising a main part drawn from an integral sheet of metal to form a pulley portion at one end and a portion of reduced diameter at the other end; said pulley portion having a fold at the inner end thereof 65 forming a flange and formed with a flange at the outer end thereof; and a separate plate forming the outer end of the pulley and having its peripheral portion in engagement with the outer flange of said pulley portion. 70

5. An automobile fan comprising the combination of a blade member; a hub-member, the latter comprising an integral seamless sheet of metal shaped to form a pulley portion and a portion of reduced diameter, together with a separate end plate secured to said pulley portion; and bushings seated in the end of said portion of reduced diameter and plate respectively; said portion of reduced diameter being secured in a central opening formed in the blade member. 75

6. An automobile fan comprising the combination of a blade member; a hub-member, the latter comprising an integral seamless 80 sheet of metal shaped to form a pulley portion, and a portion of reduced diameter, together with a separate end plate secured to said pulley portion; and bushings seated in the end of said portion of reduced diameter 85 and disk respectively; the extremity of said portion of reduced diameter projecting through a central opening formed in the blade member and turned outwardly on the exterior thereof so as to form a fold enveloping the peripheral portion of the blade member surrounding said central opening. 90

7. A main member of a fan-hub, consisting of a seamless drawn sheet metal tubular element having a pulley-portion at one end 100 and a portion of reduced diameter at the other end, a shoulder at the outer end of the pulley portion and a flange at the inner end of the latter, the outer end of the vertical portion being still further reduced, and the 105 outer end of the pulley-portion having a cylindrical portion projecting from said shoulder.

Signed by me this 12 day of October, 1921.

ERNEST H. ARNOLD.
